United States Patent Office.

JOSEPH P. WADDELL, OF BROOKHAVEN, MISSISSIPPI.

Letters Patent No. 106,239, dated August 9, 1870.

IMPROVEMENT IN MEDICAL COMPOUND OR PILL.

The Schedule referred to in these Letters Patent and making part of the same.

To all whom it may concern:

Be it known that I, JOSEPH P. WADDELL, of Brookhaven, in Lawrence county, State of Mississippi, have invented and compounded a new Pill for the curing of cholera, diarrhea, dysentery, and all diseases of the bowels, or derangements of the digestive organs, when made and compounded of the medicines, of a pure and genuine article, as named, and in quantities as described in the formula set forth.

The object of this invention is to furnish a healthy, simple, harmless medicine, adapted to the necessities of a large portion of the human family, in all diseases of the bowels and derangements of the digestive organs.

To enable others skilled in the art of combining the

medicine, I will proceed to give the formula and component parts of the same:

(2) two parts of podophyllum peltatum, (2) two parts leptandra virginica, (1) one part of capsicum, made into five-grain pills, more or less, as may be preferred.

They may also be made of the extracts of the same medicine, and in the same proportions.

What I claim as my invention, and desire to secure by Letters Patent, is—

The combination and use of the above medicine and extracts, for the purposes as stated.

JOSEPH P. WADDELL. [L. S.]
